DESIGN FOR A TOY

Albert P. Schmid and Anthony De Rose,
Philadelphia, Pa.

Application June 21, 1943, Serial No. 110,494

Term of patent 14 years

To all whom it may concern:

Be it known that we, Albert P. Schmid and Anthony De Rose, both citizens of the United States of America and residents of Philadelphia, county of Philadelphia, and State of Pennsylvania, have invented a new, original, and ornamental Design for a Toy, of which the following is a specification, reference being made to the accompanying drawing, forming part thereof and in which:

Fig. 1 is a side elevational view of a toy showing our new design.

Fig. 2 is a front elevational view of the same.

Fig. 3 is a top plan view of the same.

We claim:

The ornamental design for a toy, as shown.

ALBERT P. SCHMID.
ANTHONY DE ROSE.
